UNITED STATES PATENT OFFICE.

WILLIAM EDGAR BELL AND FRANCIS WILLIAM BROWN, OF DEVINE,
TEXAS.

LOCK.

SPECIFICATION forming part of Letters Patent No. 738,280, dated September 8, 1903.

Application filed March 16, 1903. Serial No. 148,117. (No model.)

To all whom it may concern:

Be it known that we, WILLIAM EDGAR BELL and FRANCIS WILLIAM BROWN, citizens of the United States, residing at Devine, in the county of Medina and State of Texas, have invented a new and useful Lock, of which the following is a specification.

This invention relates to locks which are applicable to a variety of purposes—such as, for instance, to house-doors, outside doors, inner safe-doors, and the like; and it has for its object to provide a lock which shall be simple in construction, easily operated, not liable to get out of order, not capable of being picked or of being operated by persons not having some knowledge of the mode of operating the lock and which, generally speaking, shall possess superior advantages in point of simplicity, durability, and general efficiency.

With these ends in view our invention consists in the improved construction, arrangement, and combination of parts, which will be hereinafter fully described, and particularly pointed out in the claims.

In the accompanying drawings, Figure 1 is a plan view of our improved lock, the front plate having been removed to expose the interior construction and the lock being shown in "locked" position. Fig. 2 is a vertical sectional view of the lock complete. Fig. 3 is a perspective view showing in detail the several parts or members combined in the make-up of the lock. Fig. 4 is a detail view of the key. Fig. 5 is a part sectional detail view of one of the latch knobs. Fig. 6 is a sectional detail view of a door-bolting device used in connection with and co-operating with our improved lock. Fig. 7 is an elevation showing the lock applied to a double door.

Corresponding parts in the several figures are indicated by similar numerals of reference.

1 designates the casing of our improved lock, which is preferably rectangular, as shown, and which is provided with a raised flange 2, against which the front plate 3 may be fitted when the parts of the device are assembled. The back plate 4 of the lock-casing and the front plate 3 are each provided with a centrally-disposed outwardly-extend-

ing boss, the one upon the back plate being designated 5 and the one upon the front plate 6. Each of these bosses is provided with a circular aperture 7, having an internal annular flange 8, which serves to retain and to guide the lock-barrel, as will be presently described.

9 designates the lock-barrel, which is provided near one end with a disk 10, having on its outer side an annular rabbet 11, which engages against the inner side of the annular flange 8 of the back plate of the lock. Both ends of the barrel are screw-threaded, and said barrel is provided at the ends thereof with slots 12 and 13, the slot 12 at the rear end of the barrel being extended through the disk 10, as will be seen at 14, thus forming a keyhole of suitable dimensions. The barrel is itself longitudinally perforated for the passage of the key.

15 designates a disk which corresponds in size and shape with the disk 10 upon the barrel, it being provided with an annular rabbet 16, adapted to bear against the annular flange 8 of the back of the lock. This disk 15 has a central screw-threaded perforation 17, whereby it is adjusted upon the rear end of the barrel until the slot 14 in the disk 10 is in alignment with a corresponding slot 18 in the disk 15. The disks 10 and 15 are then securely connected by means of screws 19, inserted through alining perforations in said disks, which are thereby connected revolvably with the flange.

20 designates the bolt-operating disk, which is centrally perforated, as at 21, to enable it to be placed upon the lock-barrel. This disk is also provided with slots 22, corresponding with the slots 14 and 18 in the disks 10 and 15. This disk 20 is provided at each end thereof with annular rabbets 23, adapted to engage the circular apertures in the back and front plates of the lock-case, respectively. Said disk is furthermore provided with circular recesses 24, one at each end, adapted to receive the loose or "floating" plates 25, which are placed loosely and revolvably in the said recesses and which are provided each with a central opening 26 to engage the lock-barrel and with a slot 27, corresponding with the slots 14, 18, and 22. The said disk 20 is

furthermore provided at diametrically opposite sides with recesses 28, in which the ends of upward and downward extending pitmen or connecting-rods 29 are pivotally mounted 5 upon transverse pivot-pins 30. These recesses 28 may be described as being at the upper and lower edges of the disk 20. Intermediately between said recesses is formed a similar recess 31, in which the lock-bolt 32 is 10 pivotally mounted upon a pin 33, the flange of the lock-case having a slot 32^a for the passage of said bolt. The edge of the disk opposite to that having the recess 31 is provided with a peripheral groove 34, constituting a 15 slide-race and terminating in recesses 35 and 36, which are disposed at the other ends of the keyhole-slots 22.

37 designates a slide secured upon and in contact with the back plate of the lock by 20 means of a keeper 38, a spring 39, bearing against the flange of the lock-case, serving to normally force the said slide in an inward direction toward the disk or plate 20 and into the slide-race 34 with one of the recesses 35 and 36, of which it is normally in 25 engagement. The inner engaging end of this slide is beveled or tapered, as will be seen at 40, and said slide is obviously made of such a shape that it will not turn in its keeper or 30 socket, thereby insuring the presentation of the beveled end at all times in the proper direction. The flange 2 of the lock-case is provided at the top and bottom thereof with perforations 41 for the passage of bolts 42, the 35 inner ends of which are pivotally connected with the outer ends of the pitmen 29, the inner ends of which have pivotal connection with the recesses 28 in the disks by means of the pins 30, hereinbefore described. The 40 outer ends of the bolts 42 are screw-threaded for convenient connection with extension-bolts 42^a, adapted to engage keepers at the top and bottom casing of the door to which the lock is applied. It is obvious that by 45 partly turning the disk 20 the bolts 32 and 42 may be withdrawn or extended, as may be required, for the purpose of opening or closing the lock, which is retained in its opened or closed position by means of the slide 37, 50 engaging one of the recesses 35 or 36. The connecting-groove between said recesses forms what we term a "slide-race," which enables the disk to be partially turned when the slide 37 is withdrawn, as will be readily understood.

A disk 43 of identical construction with the disk 15 is screwed upon the outer end of the barrel 9, thereby retaining the disk 20 and its related parts in position in such a manner as 60 to permit it to revolve freely. The front plate 3 is then mounted in position and connected with the lock-case by means of suitably-disposed screws or fastening means, and a disk 44, corresponding with the disk 43, is 65 finally screwed in position upon the extreme front end of the barrel and is connected with the disk 43 by means of fastening-screws 45.

It will thus be seen that the disks 43 and 44 are placed rotatably in engagement with the flange 8 of the front plate in like manner as 70 the disks 10 and 15 engage the flange 8 of the rear plate. It is also obvious that said disks, owing to the construction set forth, are all connected with and revolve with the central barrel 9, while the floating plates 25 are rev- 75 oluble independently of the remaining parts of the lock.

A latch 46 of ordinary construction is provided, said latch being actuated by means of a spring 47, suitably secured within the lock-cases and said latch being operated by means of wings 48 upon a stem 49, extending through the lock-case and provided with screw-threaded ends 50, upon which the handles 51 are mounted and secured in the usual manner by 85 means of set-screws 52.

In operation when the lock is bolted the slide 37 is in engagement with the recess 35 of the bolt-operating disk 20, the position of which, as indicated in Fig. 1, will be such 90 that the bolts 32 and 42 will be "shot" or extended. The key which is used in connection with this lock is provided with a central guide-rib 53 and a bit 54, provided with an angular or tapering corner 55. When said 95 key is inserted into the keyhole from either side, the lock-barrel may be turned until the keyhole-slots pass into alignment with the corresponding slot in the adjacent floating disk 25. The latter will now turn with the 100 key until the beveled or angular corner of the bit of said key passes into alignment with the recess 35, into which the beveled end of the slide 37 projects. Pressure upon the key will now still farther insert the latter into the 105 lock until the end of the slide 37 becomes disengaged from the recess 35, when it will offer no obstruction to the turning of the operating-disk to the position indicated in dotted lines in Fig. 1, when the said slide 37 will engage the recess 36, and thus retain the lock- 110 ing-disk in position, with the bolts withdrawn to an unlocked position. In the act of withdrawing the key from the lock the position of the various movable elements may be readily disturbed, so that the key may not be 115 readily inserted into the lock for the purpose of operating the same without a practical knowledge as to how the operation is to be performed.

It has been stated that the bolts 42, extending upwardly and downwardly from the lock, shall be provided with extensions 42^a, reaching to the top and bottom of the door-casing, where suitable keepers are to be provided to 125 be engaged by said bolts, as will be readily understood.

When the lock, as illustrated in Fig. 7 of the drawings, is applied to a double door, we provide an additional fastening means comprising a plate 53, which is secured to the top of the door-casing and which is provided with guides or keepers 54 55 for a pair of vertically-slidable short bolts 56 and 57, the upper

ends of which are provided with pins 58, engaging slots 59 at the outer ends of the arms of a bell-crank lever 60, which is pivotally connected with the plate 53. The slide 57 is normally kept in a raised position by means of a spring 61, interposed between its upper end and the top of the keeper 55, in which it is vertically movable, thus keeping the slide 56 normally in a depressed position, as will be seen in Fig. 6 of the drawings. The door-section 62, to which the lock is attached, is provided at its upper end with a keeper 63 for the extension-bolt 42^a, said keeper being, when the door is closed, in alinement with the keeper 54. It is obvious that when the door is closed and the lock is bolted the bolt-section 42^a will force the sliding member 56 upwardly against the tension of the spring 61, thus depressing the sliding member 57 through its housing 55 and into a keeper 64 at the upper end of the door-section 65. Both door-sections 62 and 65 will thus be securely bolted by the action of the single lock.

We desire it to be understood that while we have in the foregoing described a simple and preferred construction of our improved lock we do not thereby limit ourselves to the precise structure herein set forth, but reserve to ourselves the right to any changes, alterations, or modifications which may be resorted to within the scope of our invention and without departing from the spirit or sacrificing the utility of the same.

Having thus described our invention, we claim—

1. In a lock, a casing having front and rear plates spaced apart by a flange, said front and rear plates being provided with circular apertures having internal annular flanges disposed between the front and rear sides of the plates having said apertures, and rotary elements of the lock retained and guided by said flanges.

2. In a lock, a casing having front and rear plates spaced apart by a flange, said front and rear plates being provided with outwardly-extending bosses having circular apertures provided with internal annular flanges disposed between the front and rear sides of the plates having said apertures, and rotary elements of the lock retained and guided by said flanges.

3. A lock having casing-plates provided with circular apertures having internal annular flanges, and a rotary barrel provided at each end with a pair of disks annularly rabbeted to engage said flanges and to sustain said barrel revolvably in position and connecting means for said disks.

4. In a lock, a revolvable barrel having annularly-rabbeted end disks engaging annular flanges formed internally within circular apertures in the lock-case and connecting means for said disk, said end disk being provided with keyhole-slots and said barrel being provided with end slots alining with the keyhole-slots and with a longitudinal perforation.

5. In a lock, a lock-case having front and rear plates provided with circular apertures having internal annular flanges in combination with a barrel having screw-threaded ends and provided with a permanent end disk, annularly rabbeted upon its outer side, auxiliary disks having threaded engagement with the ends of the barrel, said disks being annularly rabbeted to engage the internal annular flanges in the circular apertures of the lock-case, keyhole-slots in the permanent and in the adjustable disks placed in alinement with each other, and connecting means for the disks at each end of the barrel.

6. In a lock, the combination of a casing, a barrel connected revolvably with the front and rear walls of said casing, connecting means supporting the ends of the barrel, means for preventing the endwise displacement of the barrel from its supporting means, an operating-disk mounted revolvably upon the barrel between the supporting means of the latter, bolts connected with said operating-disk and extending through the walls of the casing and floating plates loosely connected with said operating-disk and having keyhole-slots corresponding with keyhole-slots in the operating-disk and in the supporting member of the revolvable barrel.

7. In a lock, a casing having circular apertures in combination with an operating-disk having annularly-rabbeted ends engaging the circular apertures and thereby sustained revolvably within the lock-casing and a lock-barrel revolvable within and independently of said operating-disk.

8. In a lock, a casing having circular apertures, in combination with an operating-disk having annularly-rabbeted ends engaging the circular apertures and thereby sustained revolvably within the lock-casing, bolts connected with said operating-disk and extending through apertures in the casing and spring-actuated means engaging the operating-disk to retain the latter in position when the bolts are extended or withdrawn.

9. In a lock, an operating-disk supported revolvably within the lock-casing and having recesses connected by a peripheral slide-race, in combination with a spring-actuated bevel-ended slide adapted to engage said recesses.

10. In a lock, an operating-disk supported revolvably within the casing and having key-hole-slots, recesses at the ends of said key-hole-slots, a slide-race connecting said recesses, in combination with a spring-actuated, bevel-ended slide engaging said slide-race to limit the movement of the operating-disk and keyhole-slotted disks mounted loosely adjacent to the ends of said operating-disk.

11. In a lock, an operating-disk supported revolvably within the casing and having key-hole-slots, recesses, a slide-race connecting said recesses and provided at its ends with recesses, in combination with keyhole-slotted floating disks mounted loosely in the end recesses of said operating-disk, and a spring-ac-

tuated slide adapted to engage the recesses in the edge of said disk.

12. In a lock, the combination of a casing having circular apertures, a barrel having supporting means whereby it is mounted revolvably in said circular apertures, an operating-disk mounted revolvably upon said barrel and also supported revolvably by the apertures in the lock-casing, said operating-disk being provided with keyhole-slots, and, at the ends of said slots with recesses connected by a slide-race, a bevel-ended, spring-actuated slide adapted to engage said recesses, floating disks mounted revolvably in recesses at the ends of the operating-disk and bolts connected with the latter and extending through the lock-case, said floating disks and the supporting means of the barrel being provided with keyhole-slots corresponding to those in the operating-disk.

13. A lock having an upwardly-slidable bolt extension, in combination with a keeper for said bolt extension associated with one of a pair of folding doors to which the lock is applied, a corresponding keeper associated with the other door, and a locking device comprising keepers alining with keepers upon the doors when the latter are closed, bolt members slidable in said keepers, a lever connecting said bolt member, and means for forcing one of said bolt members normally in an upward direction.

In testimony that we claim the foregoing as our own we have hereto affixed our signatures in the presence of two witnesses.

WILLIAM EDGAR BELL.

FRANCIS WILLIAM BROWN.
